[57] **CLAIM**

The ornamental design for a food service station, as shown and described.

DESCRIPTION

FIG. 1 is a perspective view of a food service station, showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a sectional view taken along the lines 6—6 in FIG. 2.

The broken lines are for environmental purposes only and form no part of the claimed design.
